ELECTRICAL OUTLET SOCKET

Application filed June 19, 1928. Serial No. 286,520.

This invention relates to electric outlet sockets. More particularly this invention relates to the type of socket used in stringing a line of depending electric lamps across spaced supports for outdoor decoration, illumination and the like purposes.

Among the objects of this invention is to provide a device of the character and for the purpose described which shall be positively waterproof and rugged in construction, and yet be neat and compact, comprise few and simple parts, comparatively cheap to manufacture and easy to assemble, and practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims:—

Fig. 1 is a side elevational view of an embodiment of the invention with a lamp secured in place;

Fig. 2 is a cross-sectional elevational view thereof showing a lamp secured in the socket;

Fig. 3 is a bottom plan view of the insulating body with the current carrying parts removed;

Fig. 4 is a plan view of a detail;

Fig. 5 is a cross-sectional view taken on line 5—5 of Fig. 2; and

Fig. 6 is a top plan view of the insulating housing.

Referring in detail to the drawing, 10 designates an electrical outlet socket embodying the invention which is here seen to comprise a housing 11 for a screw threaded shell 12 adapted to receive the base 13 of a lamp 14 for connecting said lamp in parallel across conductors 15, 16 connected to a suitable electrical power circuit.

The housing 11 is preferably made of a molded insulating material such as porcelain, or pheno-condensate products, and is formed with a cylindrical body portion 17 having a top wall 18 and an outwardly flaring flange portion 19 at the bottom, open end thereof. Spaced longitudinal, parallel, rib-like hollow projections 20 may be provided on the housing 11 forming channel like spaces 20a on the interior of the housing for receiving the conductors 15, 16.

The shell 12 may be flared outwardly slightly at the bottom thereof as at 22 to abut the inner surface 23 of flange portion 19. An insulating disc 24 is secured to the top portion of said shell, and carries a central contact 25 for contacting the central contact of the lamp base 13, in the manner well known in the art. The conductors 15 are connected as at 15a to said central contact 25, while conductors 16 are connected as at 16a to the shell 12 by soldering, or in any other suitable manner. Thus the lamp 14, when secured in the socket is connected in parallel across the electrical power circuit.

It will be noted that the housing 11 comprises walls of substantially uniform thickness throughout. However, the inner surface 23 of flange 19 is recessed at the lower ends of channel spaces 20a, as shown by the tapering cross-sections at 26, to permit the conductors 15, 16 to extend into said channel spaces.

For sealing the space between the lamp base 13 and the flange 19 at the bottom end of the housing 11 against rain, snow or other moisture, a washer 30 is preferably provided having an opening 31 for snugly receiving the lower end 32 of the lamp base 13. Said washer is further provided with four equally spaced notches 33 adjacent the outer periphery thereof for permitting passage of the four conductor wires 15, 16 extending into the housing. The washer 30 is preferably

made of "Bakelite" or other suitable waterproof material.

It will be noted that the washer 30 rests on the portion of the bulb 14a of lamp 14 adjacent the base 13. Screwing said lamp into the shell will cause the bulb 14a to press against the washer 30 which in turn presses against the bottom portion of flange 19 and against the conductor wires 15, 16. A snug, 10 waterproof fit between the lamp and socket is thus obtained.

The socket made in accordance with the invention can be very readily and easily assembled. The conductor wires are first soldered to the shell 12 and central contact 25, and then the wires and socket inserted into the insulating body thru the flared open end with the conductors resting in the channels 20a. This enables a very quick and easy 15 assembly with the insulating body completely closed for weatherproof purposes, except at the open end wherethrough the socket is inserted and where the water-tight seal is effected by means of the disc 30 in such manner as to permit the wires to extend from the open end of the socket for further connection with other sockets, or for connection to a supply.

It will thus be seen that there is provided 30 a device in which the several objects of this invention are achieved, and which is well adapted to meet the conditions of practical use.

As various possible embodiments might be 35 made of the above invention, and as various changes might be made in the embodiment set forth, it is to be understood that all matter herein set forth or shown in the accompanying drawing is to be interpreted as 40 illustrative and not in a limiting sense.

Having thus described our invention, we claim as new and desire to secure by Letters Patent:—

1. In a structure of the character described, 45 the combination with an insulating body having an open end and being otherwise closed and a socket shell mounted in said body, of a plurality of conductor wires connected to said shell extending into said body through 50 said open end, a lamp having a base secured in said shell, and a waterproof washer receiving said base therethrough interposed between said lamp and said body, said washer having notches in the outer periphery 55 thereof receiving said conductor wires.

2. In a structure of the character described, 60 an insulating body having an open end and a socket shell mounted in said body, a plurality of conductor wires extending into said body through said open end connected to said shell, and a waterproof washer at the open end of said body, said washer having notches in the outer periphery thereof for receiving said conductor wires.

3. In combination, a molded insulating

body comprising a cylindrical housing having an outwardly flaring open end portion, a socket shell secured within said body, and conductor wires secured to said shell extending into said body at said open end. 70

4. In combination, a molded insulating body comprising a cylindrical housing having an outwardly flaring open end portion, a socket shell secured within said body, a plurality of conductor wires extending into said body at said open end and secured to said shell, and a washer member at the open end of said body, said washer having notches for receiving said wires. 75

5. In combination, a molded insulating body comprising a cylindrical housing having a flared end portion, the inner surface of said end portion having spaced recesses, a socket shell secured in said housing, a plurality of conductor wires extending into 80 said housing at said recesses and secured to said shell, a lamp having a base fitted in said shell, and waterproofing means resting on a portion of said lamp and pressing said wires against said flared portion at said recesses 85 upon attaching said lamp to said socket. 90

6. In combination, a molded insulating body having an open end portion, the inner surface of said end portion having spaced recesses, a socket shell secured within said body, a lamp having a base secured in said shell, a washer member having notches in the outer periphery thereof registering with 95 said recesses, conductor wires secured to said shell and extending into said body, each wire being received in a recess and corresponding notch, said washer member having a portion resting on a portion of the lamp adjacent the base thereof and held against said wires and body upon securing said lamp to said body. 100

7. A weatherproof electrical socket of the character described comprising a molded hollow insulating body having an open end and being otherwise completely closed, a socket shell comprising two electrical terminals insulated from one another and having conductor wires connected thereto, said socket shell and wires being inserted into said body thru said open end and held therein with the conductor wires extending from said open end. 115

8. A weatherproof electrical socket of the character described comprising a molded hollow insulating body having an outwardly flared open end and being otherwise completely closed, a socket shell comprising two electrical terminals insulated from one another and having conductor wires connected thereto, said socket shell and wires being inserted into said body thru said open end and held therein with the conductor wires extending from said open end. 120

9. A weatherproof electrical socket of the character described comprising a molded

hollow insulating body having an open end and being otherwise completely closed, said body being provided with spaced channels on the interior thereof, a socket shell comprising two electrical terminals insulated from one another and having conductor wires connected thereto, said socket shell and wires being inserted into said body thru said open end and held therein with the conductor wires disposed in said channels, with the conductor wires extending from said open end.

In testimony whereof we affix our signatures.

REUBEN ECKSTEIN.
MAX POLIS.
